SELF TYING CLIP

Edward Carson Armstead, Darrington, Wash.

Application January 10, 1934, Serial No. 706,122

1 Claim. (Cl. 256—48)

This invention relates to a clip for attaching strings, wires and the like to posts, the general object of the invention being to provide a clip having a point for penetrating the post and a curved portion for holding the string or wire against the post.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is a view of a fence or the like showing the invention in use.

Figure 2 is a fragmentary view showing one of the clips holding a string or wire to a post.

Figure 3 is a view similar to Figure 2, but looking toward the edge of the clip.

Figure 4 is an enlarged view of the clip.

As shown more particularly in Figure 4, the clip A is formed of a strip of wire or the like and is looped upon itself to form the contacting portions 1 and 2, with the free end of the part 2 bent at right angles and pointed and roughened, as shown at 3, so that this part of the clip can be forced into a post 4 to which the strings or wires 5 are to be connected by the clips. The part 1 is extended and has an intermediate straight part 6 and an inwardly bowed part 7 so that when the part 3 is forced into a post, its bowed part 7 will press against the post and thus hold a string or wire in place, the wire passing between the post and the part 6.

Thus it will be seen that I have provided simple means for holding a wire or string on a post, without using staples or looping the flexible member

about the post as is now done in placing strings on posts for supporting peas and other vines or plants.

As the device is formed of steel wire, it will give slightly as the string or wire is forced between the part 7 and the post so that the flexible member can be easily connected with the post or disconnected therefrom.

Where the post is placed in a hollow and the flexible members extend downwardly from adjacent posts, the clips can be inverted so as to prevent the strain on the members from forcing them by the bowed parts 7.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A device for fastening a flexible member to a post comprising a single piece of wire having an intermediate part adjacent one end, bent upon itself to provide inner and outer parallel portions which contact each other, the free end portion of the inner part being bent at right angles, away from the other part, and pointed and roughened to provide a post penetrating part, the inner part contacting the post when the pointed part is driven thereinto, the other end portion of the wire forming a vertical extension of the outer part, said extension having a straight lower part and an inwardly bowed upper part, the bowed part contacting the post with the straight part spaced from the post and providing a space between itself and the post to receive the flexible member.
